UNITED STATES PATENT OFFICE

CHARLES S. THOMPSON AND WILLIAM B. LONG, OF CHICAGO, ILLINOIS, ASSIGNEES TO UNION SPECIAL MACHINE COMPANY, OF CHICAGO, ILLINOIS, A CORPORATION OF ILLINOIS

FILLED-BAG-CLOSING MACHINE

Application filed December 3, 1935. Serial No. 72,941.

The invention relates to new and useful improvements in filled bag closing machines, and more particularly to a machine of this type wherein the filled bag is conveyed to the stitching mechanism by a carrier which is free to run back and forth on supports therefor.

An object of the invention is to provide a filled bag closing machine of the above type with manually controlled means for returning the carrier to its initial or starting position.

A further object of the invention is to provide a filled bag closing machine of the above type wherein said returning means is yieldingly held in position to return the carrier and is manually moved to a position to permit the free movement of the carrier along the support therefor.

20 A still further object of the invention is to provide a filled bag closing machine of the above type wherein the means for returning the carrier is moved so as to permit the carrier to run free by a treadle connection, which 25 treadle connection is so arranged that the supports for the carrier may be moved up and down for adjusting the position of the bag relative to the sewing head without in any way disturbing the treadle connections.

30 A still further object of the invention is to provide a filled bag closing machine of the above type wherein the means for returning the carrier is so constructed that the carrier may be returned at any point in its travel 35 along the support therefor.

These and other objects will in part be obvious and will in part be hereinafter more fully disclosed.

In the drawings which show by way of 40 illustration one embodiment of the invention—

Figure 1 is a front view of a filled bag closing machine embodying the improvements;

45 Fig. 2 is an end view of the machine from the left-hand side thereof as viewed in Fig. 1;

Fig. 3 is a plan view of the machine.

Fig. 4 is a plan view of the carrier and the supports therefor, showing the carrier in its 50 forward position with the returning rail in

full line position for the forward movement of the carrier, and in dotted line position for returning the carrier, also showing in dotted lines the initial starting position of the carrier, and

55 Fig. 5 is a sectional view on the line 6—6 of Fig. 1.

The invention is directed broadly to a filled bag closing machine, preferably of the column type, on which column is supported 60 a sewing head and the operating means therefor. Beneath the sewing head are supports or tracks for a carrier for the filled bag. These supports or tracks are mounted on a supporting bracket which is likewise supported by the column and is capable of being adjusted vertically thereon. The carrier is free to roll along the supports therefor. The supports are preferably provided with rollers 65 at spaced distances, and the carrier is provided with a flat plate resting on these rollers, and said carrier rolls back and forth on the rollers. Other rollers are provided for preventing the carrier from moving laterally. These supporting rollers form the track for 70 the carrier. The tracks or supports for the carrier may be horizontal, and the carrier moved along the same by the feed of the sewing machine as it stitches and closes the mouth of the bag resting on the carrier. In 75 order to aid the carrier in its free movement while sewing the bag, the tracks may be slightly inclined downwardly from the initial starting point to the point where the bag is finally closed.

80 The present invention is directed particularly to the means for returning the carrier after the bag has been closed. This means consists broadly of what might be called a third rail which extends the full length of the tracks and is pivoted to the support for the tracks at a point adjacent the initial starting point of the carrier. This third rail is 85 swung on its pivot by means of a spring, and the spring and pivot are so arranged that the third rail moves in substantially a horizontal plane. Mounted on the under side of the carrier is a bell crank carrying at one end thereof, a roller which bears against the side 90 face of this rail. The other end of the bell 95

100

crank is connected to a spring which in turn is connected to the carrier. This spring is lighter than the spring which controls the third rail. This third rail is swung on its pivot against the tension of the spring by treadle-controlled means. When the operator steps on the treadle, the third rail is shifted to a position which is substantially parallel with the tracks, and as a result, the 5 roller on the bell crank can freely run along the third rail; and the carrier can be freely moved along the tracks. This is the position of the parts when the bag is being stitched. After the bag is stitched, the operator 10 releases the third rail, and the tension of the spring on the third rail will swing it on its pivot to an inclined position relative to the direction of travel of the carrier, so that the pressure of this third rail on the roller carried by the bell crank will cause the carrier to 15 return to its initial starting position.

Referring more in detail to the drawings, the invention is shown as applied to a filled bag closing machine including a supporting base 1 preferably mounted on rollers 2, 2, and carrying an upright column 3. Adjacent the upper end of the column there is an adjustable sleeve 4 carrying a bracket 5 on which the sewing head is adapted to be secured. The sewing head is operated by a 20 suitable clutch mechanism 6 on which the clutch is shifted by a lever 7, and this lever 7 is operated by means of a cord or flexible connection 8, connected at the lower end to an arm 9 which can be depressed by the foot of the operator. This flexible cord 8 runs over idlers 10 and 11 and is connected at 12 to the upper end of the column. This provides a means for permitting the adjustment 25 of the sleeve carrying the sewing head up and down without in any way disturbing the treadle actuated means for operating the clutch. The sleeve 4 is raised and lowered by a shaft 13 which is connected to a cross 30 shaft 14 operated by a hand wheel 15. The sewing head in the present embodiment of the invention is operated by means of a motor 16 mounted on a collar 17 rigidly attached to the column 3. The belt from the motor 35 runs over idlers 18, 18 and 19 on the way to the clutch mechanism 6, and this action permits the sewing head to be raised and lowered without in any way interfering with the actuating mechanism for the sewing head. Also 40 mounted on the column 3 is another adjustable sleeve 20, and a shaft 21 in turn actuated by the cross shaft 14 is for the purpose of raising and lowering this sleeve. It is understood, of course, that the cross shaft 14 may 45 be connected either to the vertical shaft 13 or the vertical shaft 21. Mounted on this sleeve 20 are bracket arms 22, 22 which carry channel iron supports 23 and 24. These 50 channel iron supports extend from one side of the machine to the other as shown in Fig.

1 of the drawings. Mounted to move back and forth on these supports is a carrier 25. The supports 23 and 24 are substantially horizontal, and each support is provided with spaced rollers 26, 26. These rollers are mounted on rods 27 at the ends of the channel iron supports which serve to join said supports. The rollers intermediate the ends of the channel iron supports are carried by suitable supporting bolts indicated at 28 in Fig. 51 of the drawings. The carrier 25 consists of an upper plate which is bent upwardly at 25 at the rear of the supports. This plate is rigidly secured to a lower plate 29 and the plate 29 runs back and forth on the rollers 26. The rollers throughout the length of the channel iron supports form the track on which the carrier freely runs. The carrier is prevented from moving laterally by rollers 30, 30 which are rigidly fixed to the carrier and adapted to bear against guide plates 31, 31 secured to the upper face of the channel iron supports.

This column type of closing machine, so far as described, forms no part of the present invention per se, but is shown, described and claimed in the co-pending applications of Charles S. Thompson and William B. Long, Serial No. 597,615, filed October 28, 1922, and Serial No. 561,523, filed May 16, 1922.

In a machine of the above type, the carrier is free to run back and forth on these rollers and the channel iron supports are either horizontal, or substantially so, and the sewing machine feed is depended upon to move the carrier as the mouth of the bag being closed is fed by the feeding mechanism of the sewing head. The track may be slightly inclined downwardly from right to left as viewed in Fig. 1, in order to aid in the free movement 100 of the carrier by the stitching mechanism.

The present invention is directed particularly to the means for returning the carrier after the bag has been stitched. The bracket arms 22 referred to above, on which the channel iron supports are mounted, extend outwardly from the column, and on the ends thereof carry supporting angle irons 22^a, and the channel irons are attached to these angle irons. As clearly shown in Figures 3 and 4 of the drawings, there is a third rail 32 which is pivoted at 33 to one of the angle irons 22^a. This third rail lies between the channel iron supports as clearly shown in Fig. 5. This third rail 32 is likewise of angle iron construction. Pivotal connected to the lower part of the carrier at 34, is a bell crank lever 35. Said bell crank lever 35 carries a roller 36 on one end thereof. The other end of this bell crank lever is connected to a spring 37 which in turn is connected at 38 to the under side of the plate 29 of the carrier 25. This spring 37 operating on the bell crank lever 35 normally presses the roller 36 against the side face of the third rail 32. The third rail 115

extends from the point slightly to the right of the right-hand angle iron support 22^a to a point adjacent the other angle iron support at the other side of the machine.

- 5 A spring 38' is connected at 39 to the free end of the third rail 32. The other end of this spring 38' is connected to the channel iron support 24. The spring 38' is of stronger tension than the spring 37. The 10 third rail 32 is swung on its pivot 33 against the tension of the spring 38' by treadle controlled means which includes a lever arm 40 connected by a link 41 to the third rail 32. When the treadle is depressed, this rail is 15 moved to the full line position shown in Fig. 4 and when so positioned, the carrier can run along the supports therefor, the roller 36 rolling along the face of the third rail, and the carrier will not be retarded in its movement 20 to any appreciable extent. In other words, it is free to run along the supports from the right-hand end to the left-hand end thereof. When the carrier is at the right-hand end of the channel iron supports as viewed in Fig. 1, 25 it is in loading position. The filled bag to be closed is placed on the carrier and the mouth of the bag placed beneath the presser foot of the sewing head. When the sewing head is started by depressing the treadle controlling 30 the clutch 6, the feed of the machine feeding the upper end of the bag will cause the carrier to slowly move along the channel iron supports therefor. During this movement of the carrier, the treadle for shifting the third 35 rail is held depressed so that the rail is held in the position shown in Fig. 4. After the bag has been fully closed and removed from the carrier, it is desirable to move the carrier to its initial starting position. This is 40 accomplished by the operator releasing the treadle so that the spring 38' will move the third rail to the inclined position shown in Fig. 4, that is, inclined relative to the path of travel of the carrier. The pressure of the 45 third rail against the roller 36 will then cause the carrier to move to the right, or to its initial starting position. The reason for this is obvious. The pivot for the bell crank is at the right of the roller as viewed from the 50 front of the machine. The pivot point of the bell crank is fixed on the carrier, and therefore, the pressure of the spring 38' through the third rail against the roller will force the carrier to the right or to its initial 55 starting position. It will be apparent from the above that a returning means for the carrier is provided which is operated by stored power. When the rail is shifted by the treadle the spring is put under greater tension 60 and thus it is that power is stored in the spring to be utilized to force the rail back to its inclined position and the forcing of the rail back to its inclined position utilizes the stored power for returning the carrier to its 65 loading position. A suitable stop, of course,

may be provided for stopping the movement of the carrier when it reaches its initial starting position.

It will be apparent from the above description that manually controlled means has been provided for returning the carrier, and this manually controlled means can be put into operation at any point in the movement of the carrier and will return it at once to its starting position. This manually controlled means does not retard the forward movement of the carrier in any way whatever, as when in the full line position, through the depressing of the treadle, it is parallel with the path of travel of the carrier. The only way in which it could retard the travel is the friction of the pivotal mounting of the roller 36 which is negligible.

It has been stated above that the third rail is moved by a lever arm 40. This lever arm 40 is fixed to a vertical shaft 42 which is mounted in a suitable bearing 43 carried by the bracket arm 22. At the upper end of this shaft 42 is an arm 44 on which is mounted an idler 45. A cord or flexible connection 46 runs over this idler 45. It also runs over idlers 47 and 48 carried by the sleeve 20. One end of this flexible cord 46 is connected at 49 to the collar 17. The other end of this flexible cord is connected to an arm 50 mounted on a treadle shaft 51 in the base 1 of the machine. This treadle shaft is operated by a foot treadle 52. The purpose of the idlers 45, 47 and 48 is to permit the sleeve 20 to be moved up and down without interfering with or disturbing the treadle connections for shifting the third rail. The foot treadle 52 is so positioned that when depressed it will not only operate the third rail, but also the clutch of the sewing head. The arm 9 is secured to the arm 50 by a bolt and is held thereby in fixed position relative to said arm 50. By loosening the bolt the position of the arm can be adjusted. Thus it is that both the arms 50 and 9 are depressed when the treadle 52 is depressed. The shifting of the arm 9 is for the purpose of securing the proper relative length of the cables 8 and 46.

The bag to be closed is placed on the carrier and the mouth thereof placed beneath the presser foot of the sewing head. The foot treadle is depressed, and this accomplishes two functions. It connects the sewing head through the clutch 6 with the driving motor therefor. This starts the stitching mechanism of the sewing head. It also shifts the third rail to the full line position shown in Fig. 4, and this permits the carrier to move freely forward as the mouth of the bag is being stitched. When the bag has been closed, the operator releases the foot treadle which disconnects the sewing head from the motor. It also shifts the

third rail to the inclined position shown in Fig. 4, so that when the filled closed bag is lifted from the carrier, the carrier will be returned to its initial starting position.

5 This member 32 has been referred to as a third rail for the reason that the roller 36 runs along this rail during the movement of the carrier. It is not a supporting track, but it is a rail on which a roller on the carrier runs. The spring operating to move this third rail to inclined position is the operating means for returning the carrier to its starting or loading position. This spring is normally active to return the carrier or 10 15 hold the carrier at its loading position, and the return means is manually rendered inactive through the treadle control. That is, when the treadle is depressed, the third rail is moved to a position parallel with the path 20 of travel of the carrier, and will not, of course, exert any pressure on the rail which tends to return the carrier to loading position.

It will be understood, of course, that adjustment may be made so that the treadle 25 may be given a sufficient stroke to place the third rail in an inclined position to the path of travel of the carrier opposite from that shown in Fig. 4, during the forward movement of the carrier. If this third rail is inclined even to a slight extent to the path of travel of the carrier when it moves forward, it will aid in the forward movement of the carrier. By this arrangement, of course, the 30 35 third rail for returning the carrier is not only rendered inactive while the bag is being stitched, but is placed so as to actually urge the carrier forward.

It is obvious that minor changes in the 40 details of construction and the arrangement of the parts may be made without departing from the spirit of the invention as set forth in the appended claims.

Having thus described the invention, what 45 we claim as new and desire to secure by Letters-Patent, is—

1. A filled bag closing machine including 50 a supporting frame, a support for a sewing head mounted on said frame, a carrier for a filled bag, supports on which said carrier may be freely moved by the feed of the sewing head during the stitching of the bag, means for returning the carrier to starting or loading position, and manual means for 55 rendering said return means inactive while the bag is being moved along the support and stitched.

2. A filled bag closing machine including 60 a supporting frame, a support for a sewing head mounted on said frame, a carrier for a filled bag, supports on which said carrier may be freely moved by the feed of the sewing head during the stitching of the bag, spring means for normally returning the 65 carrier to starting or loading position, and

manually controlled means for rendering said spring means inactive during the stitching of the bag.

3. A filled bag closing machine including 70 a supporting frame, a support for a sewing head mounted on said frame, a carrier for a filled bag, supports on which said carrier may be freely moved by the feed of the sewing head during the stitching of the bag, means carried by the frame for the returning of the same to its loading position, and manually controlled means for rendering said return means inactive during the forward movement of the carrier.

4. A filled bag closing machine including 80 a supporting frame, a support for a sewing head mounted on said frame, a carrier for a filled bag, supports on which said carrier freely moves during the stitching of the bag, a rail mounted on said frame, a roller yieldingly mounted on the carrier and adapted to bear against the side face of the rail, means for moving said rail from a position parallel with the path of travel of the carrier to a position inclined thereto, whereby the rail operating on the roller on the carrier will return the carrier to normal starting position, and means for shifting said rail to parallel position.

5. A filled bag closing machine including 90 a supporting frame, a support for a sewing head mounted on said frame, a carrier for a filled bag, supports on which said carrier freely moves during the stitching of the bag, a rail mounted on said frame, a roller yieldingly mounted on the carrier and adapted to bear against the side face of the rail, means for moving said rail from a position parallel with the path of travel of the carrier to a position inclined thereto, whereby the rail operating on the roller on the carrier will return the carrier to normal starting position, and means for shifting said rail to parallel position, said last-named 100 means including a treadle.

6. A filled bag closing machine including 110 a supporting frame, a support for a sewing head mounted on said frame, a carrier for a filled bag, supports on which said carrier freely moves during the stitching of the bag, a rail pivotally mounted on said frame and adapted to swing in a horizontal plane from a position parallel to the path of travel of the carrier to a position inclined thereto, a lever pivotally mounted on the carrier, a roller mounted on said lever and adapted to run along the face of said rail, a spring 120 adapted to hold the roller in contact with the rail, a spring of greater tension for moving said rail to inclined position, in which position the carrier is caused to return to normal loading position, and treadle controlled means for moving said rail against the tension of the spring to parallel relation 130

to the path of travel of the carrier.

7. A filled bag closing machine including a supporting frame, a support for a sewing head mounted on said frame, a supporting bracket carried by the frame and vertically adjustable thereon, a carrier for a filled bag, supports carried by said bracket on which said carrier freely moves during the stitching of the filled bag, means whereby stored power 10 may be utilized for returning the carrier to loading position, and treadle controlled means for rendering said stored power returning means inactive, said treadle controlled means operating to store power in 15 said returning means when the same is rendered inactive.

8. A filled bag closing machine including a supporting frame, a support for a sewing head mounted on said frame, a supporting bracket carried by the frame and vertically adjustable thereon, a carrier for a filled bag, supports carried by said bracket on which said carrier freely moves during the stitching of the filled bag, a rail pivotally mounted on 20 said bracket and adapted to swing in a horizontal plane from a position parallel with the path of travel of the carrier to a position inclined thereto, a roller yieldingly mounted on the carrier and adapted to run along the 25 vertical face of said rail, a spring for shifting said rail to inclined position, and treadle controlled means for moving the rail to parallel position, said treadle controlled means including devices which permit the bracket 30 to be raised or lowered without disturbing the connections to the treadle.

9. A filled bag closing machine including a supporting base, a column carried thereby, a sleeve adjacent the upper end of said 40 column, a support for a sewing head carried on said sleeve, operating means for the sewing head including a clutch mounted on said sleeve, a bracket mounted on said column and vertically adjustable thereon, a carrier 45 for a filled bag mounted on said bracket and movable back and forth beneath the sewing head, means for normally returning said carrier to initial starting position, treadle controlled means for operating said clutch 50 for the sewing head, and treadle controlled means for rendering said return means for the carrier inactive during the stitching of the bag, said treadle controlled means for the clutch and said treadle controlled means for the 55 carrier being associated whereby the operation of the clutch to start the sewing head will render the return means for the carrier inactive.

10. A filled bag closing machine including 60 a supporting base, a column carried thereby, a sleeve adjacent the upper end of said column, a support for a sewing head carried on said sleeve, operating means for the sewing head including a clutch mounted on said 65 sleeve, a bracket mounted on said column and

vertically adjustable thereon, a carrier for a filled bag mounted on said bracket and movable back and forth beneath the sewing head, means for normally returning said carrier to initial starting position, treadle controlled 70 means for operating said clutch for the sewing head, and treadle controlled means for rendering said return means for the carrier inactive during the stitching of the bag, said treadle controlled means for the clutch and 75 said treadle controlled means for the carrier being associated whereby the operation of the clutch to start the sewing head will render the return means for the carrier inactive, both the treadle controlled means for the clutch and the treadle controlled means for the return means for the carrier including devices whereby either the sewing head or the carrier may be raised and lowered relative to each other without disturbing the treadle 80 connections.

In testimony whereof, we affix our signatures.

CHARLES S. THOMPSON.
WILLIAM B. LONG.
